METHOD FOR THE OBTENTION OF PHENOLS
FROM COAL TARS AND LIGNITE TARSKurt Gieseler, Breslau, Germany, assignor to
Oberschlesischer Berg-und Hüttenmännischer
Verein e. V., Gleiwitz, GermanyNo Drawing. Application July 22, 1931, Serial
No. 552,539. In Germany July 22, 1930

1 Claim. (Cl. 260—154)

Hitherto the coal tars and lignite tars and the products of distillation of the same have been obtained in that the oils are shaken with diluted alkalis, the alkaline aqueous phenolate solution is separated, and from the same by means of acids especially carbon dioxide the phenols are separated again. The alkali, which has been used, is regenerated with caustic lime, this although it can be carried out increasing the expenses.

Another method, in which the phenol-containing oils are treated with alcohol, obtains a good separation in lignite tars which contain up to 15% phenols, but is not applicable to tars with 15% and more phenol content as the alcohol then dissolves considerable quantities of hydrocarbons.

It has further been proposed to carry out the decomposition of the tars mentioned by means of sodium carbonate solution, ammonia water, ammonia and alcohol, liquefied ammonia, alcohol and caustic soda, formic acid, petrol ether-methyl alcohol, sodium sulphide solution, superheated steam and other media.

Up to the present it has however not been possible, to effect on a large scale a complete separation of the hydrocarbons from the phenol by means of the proposed liquefied ammonia, which is a medium easily obtainable and cheap, and which can also be easily recuperated. According to this known proposal, the liquefied ammonia has to act upon the tars during several days, when a stratum formation occurs. The mixture has then to be solidified at the temperatures of the liquid air, whereupon the upper stratum is caused to melt and separated from the still solid lower stratum. Neither enriching nor reduction of the phenols in the individual stratum has been thereby obtained.

According to the invention an almost complete separation of the tars into phenols and hydrocarbons can however be effected in that the tars or the distillates of the same are treated with the liquefied ammonia only during a short time, and the strata formed are separated in the liquid condition the one from the other by suitable devices, for instance after the manner of a separation funnel standing under pressure. The neutral constituents of the tars are, at suitable mixture proportions and temperatures, soluble only in small measure in liquefied ammonia, whereas the acid constituents are dissolved therein almost quantitatively. These acid constituents form with the liquefied ammonia a homogeneous stratum, which separates above the neutral oil, con-

taining only little ammonia. Both strata can be easily separated in the liquid condition. After the ammonia has been driven out for recovery, the crude phenols are obtained with a degree of purity up to 85%. The method may also be carried out continually working.

As, especially in tar oils having a low boiling point, the crude phenol is obtained sometimes with only a low degree of purity, the method can be further developed in the following manner:

To the tar-ammonia mixture 3 to 10% of water or aqueous alcohol, such as methyl-alcohol or ethyl-alcohol or of any other organic solvent, such as acetone are added from the beginning. The solubility of the neutral oils in the ammonia-phenol stratum is thereby reduced, and the yield in neutral oils as well as the purity degree of the crude phenol are increased. It is advisable to start from hydrated crude tars.

Example 1

A distillate from coal tar, boiling at from 180 to 250° C., consisting of phenols 52%, bases 4% and neutral oil 44%, is treated with liquefied ammonia in being stirred at -50° C. Two strata are formed instantaneously, the lower one of which being consistent and light colored, whereas the upper film is dark colored. After the separating of the strata and the distilling off of the ammonia, the lower stratum consists of neutral oil 99%, phenols 0.8% and traces of bases, whereas the upper stratum is composed of phenols 80.5%, bases 6% and neutral oil 13.5%.

Example 2

In a vessel under pressure a coal tar distillate possessing a boiling point above 250° C., consisting of 55% neutral, 41% acid and 4% basic constituents, is shaken with liquefied ammonia at +15° C. and allowed to settle. The lower stratum which is formed is withdrawn, liberated from the ammonia and consists then of 94% neutral, 2% basic and 4% acid constituents. The upper layer is composed of 83% acid, 11% neutral and 6% basic parts.

Example 3

A crude lignite or tar containing 86% of neutral, 1% basic and 13% acid constituents, is mixed in a vessel under pressure with liquefied ammonia at 15 to 20° C. and the mixture allowed to settle. The lower stratum, 83% of the tar used still contains 1.2% phenols. The upper layer after removing the ammonia contains 75% pure creosote.

Example 4

- One part by weight of the whole distillate of a lignite tar is mixed with 0.7 parts by weight of liquefied ammonia and 0.05 parts by weight of water and then allowed to settle; the separated crude creosote, after the removal of the ammonia, contains 85% pure creosote, whereas, when treated without the addition of water, it has only a 10 degree of purity of 55%.

Example 5

- The total distillate of the same tar is mixed 15 with liquefied ammonia and 3 to 10% methyl-alcohol of 50% and allowed to settle to form layers. After separating the layers in liquid condition, the crude creosote has a degree of purity of 90%.

20

Example 6

- The total distillate of the same tar is treated with liquefied ammonia and 3-10% ethyl-alcohol. After separating the layers formed the crude creosote has a degree of purity of 90-95%.

Example 7

- A crude lignite tar is mixed with liquefied ammonia with an admixture of 5 to 10% acetone in a suitable pressure vessel and allowed to settle to form layers. The separated upper layer contains 90% pure creosote after removing the ammonia.

5

Example 8

- A crude coal low temperature tar containing 10 5% water is treated with liquefied ammonia with an admixture of 5 to 10% of a mixture of methyl alcohol and ethyl-alcohol and allowed to settle into layers. The separated crude creosote has a degree of purity of 90 to 95%.

15

I claim:—

- Method for the obtention of high percent phenol products, containing 80 to 90% of phenol from raw coal tars and lignite coal tars by treating tars in any state with liquefied ammonia, 20 separating after the stratum layer formation the strata in liquid condition the one from the other and removing the ammonia, consisting in adding to the tar-ammonia mixture up to 10% of water.

KURT GIESELER.
